UNITED STATES PATENT OFFICE.

JOSEPH N. KLEMA, OF AUSTIN, MINNESOTA.

LANTERN.

1,335,841.

Specification of Letters Patent.

Patented Apr. 6, 1920.

Application filed July 19, 1919. Serial No. 312,015.

To all whom it may concern:

Be it known that I, JOSEPH N. KLEMA, a citizen of the United States, residing at Austin, in the county of Mower and State 5 of Minnesota, have invented certain new and useful Improvements in Lanterns, of which the following is a specification, reference being had to the accompanying drawings.

This invention relates to certain improvements in lanterns and is an improvement 10 on the construction embodied in my co-pending application Serial No. 263,336, and it is an object of the invention to provide novel and improved means whereby a color 15 screen may be readily and conveniently supported with respect to the burner of the lamp and whereby the color screen may be raised or lowered as the occasions of practice may require.

20 The invention consists in the details of construction and in the combination and arrangement of the several parts of my improved lantern whereby certain important advantages are attained and the device rendered simpler, less expensive and otherwise 25 more convenient and advantageous for use, as will be hereinafter more fully set forth.

The novel features of my invention will hereinafter be definitely claimed.

30 In order that my invention may be the better understood, I will now proceed to describe the same with reference to the accompanying drawings, wherein:

Figure 1 is a fragmentary view partly in 35 section and partly in elevation illustrating a screen holder constructed in accordance with an embodiment of my invention, and in applied position.

Fig. 2 is a view in perspective of my 40 improved holder as herein disclosed with the coacting screen being indicated by dotted lines.

Fig. 3 is a fragmentary view in side elevation of the upper portion of my improved 45 holder, the coacting portion of the screen being indicated by dotted lines.

As disclosed in the accompanying drawings, C denotes a casing having its top or upper face open and arranged within said 50 casing at substantially the axial center thereof is the well W. Coacting with the well W in a conventional manner is the burner B. The side wall of the casing C is provided with a vertically disposed slot 1 55 extending substantially the entire length thereof and through which extends an out-

standing arm 2 extending outwardly from the lower end portion of the screen holder H.

As herein embodied the screen holder H comprises an elongated flat strip preferably 60 of metal and with the lower end portion of which the arm 2 is integrally formed. The arm 2 is substantially at right angles to the strip 3 with its side or flat faces vertically disposed.

The arm 2 inwardly of its outer end is provided with the oppositely directed wings 4 which overlie the outer and inner faces of the side wall of the casing C so that the arm 2 is conveniently supported for sliding 70 movement along the slot 1 and is maintained substantially in a horizontal position or in a position at right angles to the side wall of the casing C. In the present embodiment of my invention each of the wings 4 is preferably 75 separable from the arm 2 but is secured thereto through the medium of the rivets 5 or the like.

The lower end portion of the strip or member 3 is provided with the oppositely 80 directed arcuate arms 6. Each of the arms 6 is relatively short and is provided at its outer extremity with the upwardly facing hook member 7 in which is adapted to seat the lower end portion of the color screen S. 85 Each of the hook members 7 preferably comprises a flat arm a integrally connected with the lower marginal portion of an arm 6 and depending therefrom with the outer or free end portion b thereof bent inwardly 90 and upwardly.

Pivottally engaged with the upper end portion of the strip or member 3 inwardly thereof and for swinging movement about substantially a horizontal axis is a clip 8. The 95 working end portion of the clip 8 is outwardly offset so that the same may be readily engaged over the upper portion of the screen S so that said screen will be effectively held by the holder H. To further 100 facilitate the maintenance of the screen S in applied position I find it of advantage to employ the spring 9 for frictional contact with the outer surface of the screen S. As herein disclosed the spring 9 is integrally 105 formed with a washer 10 mounted upon the pivot 11 between the strip or member 3 and the clip 8.

It is also preferred that the arm 2 hereinbefore referred to be produced by initially twisting the lower end portion of the strip or member 3 a one-quarter turn and

then bending such twisted portion substantially at right angles to the strip or member 3.

The operation of my improved holder is substantially the same as set forth with respect to the holder as embodied in my co-pending application Serial No. 263,336 and for this reason a detailed statement of the operation is believed unnecessary.

10 In all instances it is not necessary that the spring 9 be employed because by bending outwardly the upper portion of the strip 3, the clip 8 can be caused to have the requisite contact with the upper portion of 15 the screen S. For this reason it is to be understood that the strip 3 is of a metal or other material which is capable of being bent or sprung.

From the foregoing description, it is 20 thought to be obvious that a lantern constructed in accordance with my invention is particularly well adapted for use by reason of the convenience and facility with which it may be assembled and operated and it 25 will also be obvious that my invention is susceptible of some change and modification without departing from the principles and spirit thereof and for this reason I do not wish to be understood as limiting myself 30 to the precise arrangement and formation of the several parts herein shown in carrying out my invention in practice except as hereinafter claimed.

I claim:

35 1. In a lantern, the combination with a

casing provided with a slot in the side wall thereof, a holder for a color screen comprising an elongated and vertically disposed screen supporting member, an outstanding arm carried by the lower end portion of the member and extending through the slot of the casing, oppositely directed arms carried by the lower portion of the screen supporting member, the outer portions of each of said arms being provided with upwardly facing hook members, and a clip carried by the upper portion of the member.

2. In a lantern, the combination with a casing provided with a slot in the side wall thereof, a holder for a color screen comprising an elongated and vertically disposed screen holder member, an outstanding arm carried by the lower end portion of the member and extending through the slot of the casing, oppositely directed arms carried by the lower portion of the screen supporting member, the outer portions of each of said arms being provided with upwardly facing hook members, a pivoted clip carried by the upper portion of the member, and a spring carried by the upper portion of the member between the member and the clip.

In testimony whereof I hereunto affix my 65 signature in the presence of two witnesses.

JOSEPH N. KLEMA.
